UNITED STATES PATENT OFFICE.

JAMES H. FOSTER, OF CLEVELAND, OHIO, ASSIGNOR TO THE HYDRAULIC PRESSED STEEL COMPANY, OF CLEVELAND, OHIO, A CORPORATION OF OHIO.

BARREL.

1,262,766.

Specification of Letters Patent. Patented Apr. 16, 1918.

Application filed March 10, 1911. Serial No. 618,589.

To all whom it may concern:

Be it known that I, JAMES H. FOSTER, a citizen of the United States, residing at Cleveland, in the county of Cuyahoga and State of Ohio, have invented a certain new and useful Improvement in Barrels, of which the following is a full, clear, and exact description, reference being had to the accompanying drawings.

This invention relates to barrels, and has for its object to produce a device of this character which shall be composed of the fewest possible number of parts and capable of production with the smallest possible number of operations consistent with strength; also to provide a device of this character having the smallest possible number of joints or seams through which leakage might take place; also to produce a barrel which shall possess great strength at the points where strength is most needed; also to produce a barrel having such strength although made from thinner and lighter metal than has heretofore been employed. All these and other objects, which will be made apparent in the course of the following description, are obtained by the device illustrated in the accompanying drawings, in which Figure 1 is a vertical sectional view of a barrel made in accordance with my invention and showing the barrel head applied, but not secured in place; Fig. 2 is a detail sectional view illustrating the manner of securing the inserted head to the barrel; Fig. 3 is a similar view of the lower end of the barrel; Fig. 4 is a sectional detail of the lower end of the barrel showing in dotted lines the position of the bottom or fixed head and body of the barrel and in full lines the position of the body and bottom after the first step in forming the bottom chime; and Fig. 5 is a transverse sectional view of a portion of the barrel body.

The barrel is preferably composed of a single piece of metal, and is made by pressing a flat sheet of metal into the form of a cylinder having one end closed. In forming the lower end of the barrel, the bottom or fixed head 1 is pressed into the cylindrical blank, leaving a depending cylindrical skirt formed of the doubled metal, as shown at 2, in Fig. 4. For the purpose of providing a chime of sufficient strength as well as for the purpose of reinforcing the bottom, this skirt is then rolled inwardly and pref-

erably into contact with the bottom 1, thus forming a rounded chime 2^a, the extreme end portion 2^b of which abuts against the bottom head, the bottom and the chime thus strengthening each other through their inter-engagement.

The sides of the cylindrical blank are next pressed outwardly between suitable dies, so as to form the flaring or bilged body 3 of the barrel, the dies being so constructed as to form at the same operation the longitudinal stiffening corrugations 4 in such body.

The barrel head is made in the form of a flat circular plate 6 having an annular rim 7 turned inwardly at an acute angle, and the total diameter of said head is such as to permit it to be inserted within the cylindrical neck or extension 5 and to be seated upon the ends of the corrugations 4.

A ring 8 of solder, Norway iron, fusible wire, or other suitable material or packing is now placed in the trough formed between the rim 7 and the neck or extension 5. When the metal is inserted into this trough, heat is applied to fuse the metal and to produce a closed joint at the bottom of the trough by the so-called process of "autogenous welding," after which the neck or extension will be forced inwardly into parallelism with the rim 7 and in contact therewith, after which the two thicknesses of metal are rolled inwardly to form a rounded chime, as shown at 9. The edges of the two thicknesses are preferably bent into engagement with the head, as shown at 10, thus reinforcing the head and the edge of the chime by the inter-engagement of one with the other. As will appear more particularly from Fig. 2, the lower ends of the overlapping thicknesses or plies of metal are directed outwardly, as shown at 11, whereby, should the head 6 fail for any reason to be properly supported by the internal seat, it will be supported against inward movement by the overlapping end of the neck or barrel extension.

The two chimes formed at the opposite ends of the barrel are of substantially the same shape, thus rendering the barrel symmetrical in construction and appearance.

The manner in which the end of the barrel—whether it be the neck 5 or the outer thickness of the skirt 2—is bent into engagement with the adjacent head is extremely important. It will be observed, by

reference to Figs. 1, 2 and 3, that a line of contact is formed between the end of the barrel, thus rolled inwardly, and the adjacent head in a substantially circular line 5 which is located within and at a considerable distance from the joint which is formed between the head and the barrel body. As a result of this construction, the pressure exerted by the contents of the barrel upon either one of the heads 1 and 6 will 10 press the central portion of the head downwardly, but, because of the line of contact between the chime (formed by bending the body inwardly) and the head, the outer portion 15 of the head will be flexed upwardly in a direction to tend to close the joint between the peripheral portion of the head and the body, instead of tending to open the same. This has been found to be extremely 20 important in the construction of barrels from light gage metal, since it insures ample strength in the heads while permitting the use of such light metal.

The construction above described is particularly 25 advantageous in that it permits the use of unusually thin metal without decreasing detrimentally the stiffness or strength of the barrel. The thickness of metal which can be employed is about six one-hundredths 30 of an inch. The formation of the chimes in the manner described gives them sufficient strength to withstand all ordinary incidents of use. Furthermore it will be noted that I have produced a barrel wherein there is provided 35 a bilged body having at each end a head which is set within a rim, the rims being forced inwardly in such manner as to press against their respective heads and to form chimes and that the exterior surface of 40 the barrel, including said chimes, forms a substantially continuous and unbroken curved surface, whereby a maximum strength is provided, the operation of riding the barrel is facilitated, injury to the chimes by the 45 riding operation is minimized, and the heads are strengthened by the chimes. Although I have described my barrel as made by pressing a flat sheet, it is obvious that many of the advantages thereof could be obtained by 50 rolling an elongated strip of metal into a cylindrical form and brazing, welding, or riveting the ends together. All these, and other modifications I consider within the scope of my invention, excepting as limited 55 by the prior state of the art and by the terms of the claims hereunto annexed.

Having thus described my invention, what I claim is:

1. A metal barrel comprising a hollow 60 body having an integral head with a double wall of metal surrounding and extending beyond the head and pressed inwardly to provide a double-walled chime.

2. A metal barrel comprising a hollow 65 body having an integral head with a double

wall of metal surrounding and extending beyond the head and pressed inwardly to provide a double-walled chime engaging the said head.

3. A metal barrel comprising a hollow 70 body having an integral head with a double wall of metal surrounding and extending beyond the head and pressed inwardly to provide a rounded double-walled chime engaging the said head in a line within and 75 spaced from the junction of the head and body.

4. A metal barrel comprising a body having at an end a head set within a rim, the rim being forced inwardly into engagement 80 with its head to form a chime which presses against the head in a line within and spaced from the junction of such head and body.

5. A metal barrel comprising a body having a neck at one end thereof, a head having an outwardly extending flange welded to said neck, the neck and flange thus united being pressed inwardly to provide a double-walled chime.

6. A metal barrel comprising a body having a neck at one end thereof, a head having an outwardly extending flange welded to said neck, the neck and flange thus united being pressed inwardly to provide a double-walled chime engaging said head.

7. A metal barrel comprising a body which is provided with longitudinal reentrant corrugations terminating short of an end of said body whereby shoulders are provided by the ends of said corrugations, said shoulders being located in a common plane, and a flanged head adapted to fit within such end of the body and to rest upon said shoulders, the head flange and the projecting end of the body being forced inwardly together 105 to provide a chime.

8. A metal barrel comprising a body having a head formed integral therewith and connected thereto by a reversely bent rim, the double wall of the metal of said rim being forced inwardly to form a chime, and a head within the opposite end of said body, there being a double wall of metal provided between such end and the head, and such double wall of metal being forced inwardly 110 to form a chime.

9. A metal barrel comprising a body having a head formed integral therewith and connected thereto by a reversely bent rim, the double wall of the metal of said rim being forced inwardly to form a chime engaging said head, and a head within the opposite end of said body, there being a double wall of metal provided between such end and the head, and such double wall of metal 115 being forced inwardly to form a chime engaging said head.

10. A metal barrel comprising a body having a head formed integral therewith and connected thereto by a reversely bent rim,

the double wall of the metal of said rim being forced inwardly to form a chime engaging said head in a line within and spaced from the junction of the head and body, and
5 a head within the opposite end of said body, there being a double wall of metal provided between such end and the head, and such double wall of metal being forced inwardly to form a chime engaging said head in a

line within and spaced from the junction of the head and body.

In testimony whereof, I hereunto affix my signature in the presence of two witnesses.
